United States Patent Office

Des. 185,325
Patented May 26, 1959

185,325

LAVATORY CABINET OR SIMILAR ARTICLE

John W. Shirley, Indianapolis, Ind., assignor to Shirley Corporation, Indianapolis, Ind.

Application March 11, 1957, Serial No. 45,205

Term of patent 14 years

(Cl. D4—2)

Fig. 1 is a view in front perspective of the lavatory cabinet or similar article.

Fig. 2 is a view in side perspective of the lavatory cabinet or similar article.

Fig. 3 is an elevational view of the side opposite from that as shown in Fig. 2.

The dominant features of the design reside in the portions shown in full lines.

I claim:

The ornamental design for a lavatory cabinet or similar article, as shown and described.
